MULTIPLE CIRCUIT CONNECTOR OF THE
PLUG TYPE

Hans P. Luhn, Armonk, N. Y., assignor to International Business Machines Corporation, New York, N. Y., a corporation of New York

Application March 29, 1944, Serial No. 528,656

5 Claims. (Cl. 173—328)

1 This invention relates to circuit connectors and generally to the detachable plug type for making multiple circuit connections at will. More specifically the invention relates to multiple circuit connectors of the plug type wherein circuit connections can be made by the attachment of associated connector units and conversely circuit connections can be broken by detachment of the associated connector units.

The main object of the invention is to provide an improved construction of circuit connector wherein a plug connector of a limited area can provide for a larger number of circuit connections than generally possible heretofore, and a more specific object in this connection is to devise a circuit connector which will not only provide for an increased number of circuit connections but enable efficient circuit connections as well.

Another object of the invention is to provide a circuit connector which consists of three interconnecting units, an intermediate connector unit, and a pair of connector units joined at each side of said intermediate connector unit.

An advantage following from the preceding construction and which fulfills another object is that each of the outside connectors can be provided with means to receive plug connections which can be altered at will without changing the plug connections made to the other outside connector. This flexibility is of a decided advantage for circuit connections in some electrical systems.

Another object of the invention is to provide means to assemble a plurality of such associated units whereby circuit connections can be multiplied to the required number and nevertheless retain the principal advantages of the elementary system.

This object may be carried out by providing an intermediate frame to which is assembled a plurality of intermediate connector units and other frames for carrying a plurality of the plug connector units of the other type, that is, the type which provides for the desired plug connections.

The assembly of plug connectors provides a panel or plugboard which can be detached from the intermediate connectors and allows another plugboard having different plug connections to be substituted. The same advantages are in this multiple arrangement as in the elementary system, namely, that the plug connections on the plug connectors can be varied at will without altering the plug connections of the other plug connectors.

2 Other objects of the invention will be pointed out in the following description and claims and illustrated in the accompanying drawings, which disclose, by way of example, the principle of the invention and the best mode, which has been contemplated, of applying that principle.

In said drawings:

Fig. 1 is an end view of each of the three connector units showing the association of the three units of the elementary system.

Fig. 2 is a fragmentary view in side elevation of the intermediate connector.

Fig. 3 is an end view of the intermediate connector.

Fig. 4 is a sectional view taken on the line 4—4 of Fig. 2.

Fig. 5 is a plan view of the intermediate connector.

Fig. 6 is a fragmentary view in side elevation of one of the outside plug connectors.

Fig. 7 is a fragmentary plan view of the plug connector shown in Fig. 6.

Fig. 8 is an end view of the plug connector shown in Figs. 6 and 7.

Fig. 9 is a sectional view taken on the line 9—9 of Fig. 6.

Fig. 10 is a view taken on the line 10—10 of Fig. 6.

Fig. 11 shows the preferred construction of the multiple jack.

Fig. 12 is a fragmentary plan view showing the supporting frames which carry the assembly of the different connector units to multiply the circuit connections to make up a plugboard.

Fig. 13 is a fragmentary plan view of one of the outside frames.

Fig. 14 is a view showing the three connector units joined together in contact relationship, and when mounted in the frames of Fig. 12 show how the frames are closed upon each other to secure a contact relationship between the connector units.

The three principal elements of the improved connector are shown associated in Fig. 1 and shown joined in interlocking contact relationship in Fig. 14. The improved plug consists of an intermediate connector unit 10 and cooperating outside plug connector units 11 and 12. The plug connector unit 11 has wire connections 13 and the plug connector unit 12 has wire connections 14. When the units 10, 11 and 12 are joined in contact relationship as in Fig. 14 the wires 13 are electrically connected through the units to the wires 14 for desired circuit connections.

The specific construction of the intermediate connector 10 will now be explained, particularly in connection with Figs. 2, 3, 4 and 5.

As shown in Fig. 5, the framework of connector 10 consists of an intermediate block 15 and parallel blocks 16 and 17. The blocks 16 and 17 are spaced apart from the intermediate block 15 by spacing members 18 and 19. These blocks are formed of any desirable insulating material and when in assembled relationship provide the supporting means for one or more series of projecting contact blades 20. Each connector may be assembled to provide the supporting means for the desired number of contact blades 20, but as shown herein the elements 15, 16 and 17 provide the support for two series of contact blades 20 with ten in each series. The intermediate block 15 is provided with two series of slots 21 and likewise the block 17 is provided with two series of slots 22 and such slots receive the spring blades 20 to 20 not only suitably space them in insulating relationship but also to provide a support for such blades. Each contact blade 20 is provided with shoulder portions 23 and 24 fitting in the related slots 21, 22 of the blocks 15 and 17, respectively. Of course, the block 16 in cooperation with the block 15 also secures the contact blades 20 of the other series in a similar manner. When all of the parts are in the assembled relationship, shown in Fig. 5, the blocks 15, 16 and 17 are 30 fastened together by a tubular rivet 25 at one end and a similar form of rivet 26 at the other end (see Fig. 14). By the above preferred construction the intermediate connector 10 provides for a suitable spacing of the contact blades 20 and 35 mounting thereof.

The plug connector units 11 and 12 which are joined to each side of the intermediate connector 10 are alike in construction. The description will be confined to only one of these plugs connectors with particular reference to Figs. 6 to 10, inclusive. Each plug connector 11 or 12 consists of a main body portion 30 which is rectangular in shape conforming to the length and width of the intermediate connector 10. This main body portion is made of insulating material, either molded to the desired shape or formed by machining.

The main body portion has extending therefrom a comblike structure consisting of teeth 32 and intermediate recesses or channels 33. Within these channels 33 are interposed the resilient contact blades 34 and 35. Each row of contact blades 34 consists, as shown in Fig. 14, of five contact blades bent in one direction and in the adjacent row the series of five contact blades 35 are similarly formed but are bent in opposite directions. Therefore, there is disposed in each channel 33, but in two adjacent rows so as to be separated from each other, a contact blade 34 which is adapted to make firm electrical contact with a blade 20 and also a contact blade 35 adapted to make electrical contact with the adjacent blade 20. The adjacent pairs of blades 20 are spaced apart, equivalent to the width of the channel 33 so that as plug connector 11 or 12 is joined to the intermediate connector 10, one of the blades 20 of each pair will slide between the contact blade 34 and the surface 36 (Fig. 6) of the channel and the adjacent contact blade 20 will slide between the contact blade 35 and the surface 37 (Fig. 6) of the same channel 33. The blades 34 and 35 are resilient and while slightly displaced from normal position by a blade 20 as shown in Fig. 6, nevertheless the extremities are

not moved sufficiently so that they make contact with the adjacent blade 20 at the other side of the channel 33. This keeps the circuit connection established through the contact blades 34 and 35 independent to thereby eliminate any possible back circuits. To facilitate the joining of the connectors 10 and 11, or 10 and 12, the channels 36 are machined to provide flared edges 38 whereby blades 20 are guided to contact making position.

Any suitable means for carrying the contact blades 34 and 35 can be provided but consists preferably of a construction which enables the contact blade carrying units to be manufactured alike, irrespective of the fact that the blades 34 and 35 extend in opposite directions. Furthermore, it is preferable to make such contact blade carrying units of such construction that there is formed at the extremity opposite the blades 34 or 35 jacks 44 in which plugs may enter to make the desired electrical connections. These plugs are designated by 40 in Fig. 14 and are soldered to the extremities of the wires 13 or 14.

The construction of each blade carrying unit is best shown in Fig. 11 wherein it will be seen that it consists of parallel cylinders 41 and 42 which are separated from each other by an integral strap 43 but electrically connected by such strap. The contact blade 34 or 35 is an integral extension of cylinder 42. The plugs 40 are entered in the jacks 44 formed at the ends of the cylinders 41 and 42 to provide the desired plug connections. While generally only one plug connection is usually made, the duplex jack construction provides for two plug connections for the same contact blade which is sometimes desirable.

In Fig. 18, it will be observed, that for each row of contact blades 34 or 35 ten holes are provided to receive five of the units shown in Fig. 11. 40 In the adjacent row to the left where the same number of holes are provided to receive a similar number of blade carrying units such holes are staggered (see Figs. 13, 7 and 10). Now referring to Figs. 6 and 7, it will be seen that in the right hand row the units 41, 42 of Fig. 11 are mounted so that the contact blades 35 extend in one direction. A unit 41, 42 can be inserted in the holes until strap 43 abuts the bottom of channel 33. By insertion of the units 41, 42 in the holes of the adjacent row but turned oppositely, it will be seen that the blades 34 will be disposed in the channels 33 but extend in an opposite direction. Hence, this enables the blade carrying units of Fig. 11 to be manufactured alike but by assembling them oppositely with respect to adjacent rows, contact blades 34 and 35 extend in opposite directions. To securely hold contact blade carrying units 41, 42 within the holes of the block 30, the jack formed extremities of the cylinders are cut to provide locking portions 45 which extend above the plane of the block 30 and which may be suitably offset or bent away from the cylinders 41 and 42 as shown in Fig. 10 to effectively lock with cooperation of strap 43, the blade carrying unit in assembled position. It is, of course, obvious that by the construction just described the jacks 44 of adjacent rows are staggered to provide a more convenient means of fitting the plugs 40 therein. This also reduces the possibility of short circuits in the event that a non-staggered arrangement was utilized.

It is further evident that since the intermediate connector 10 provides for five circuit connections for each row and therefore ten circuit connections for two rows, the associated plug con-

nectors 11 and 12 of the same size also provide for the same number of circuit connections. The two jacks 44 for each unit 41, 42 enable the possibility of two circuit wire connections 13 to one or two wire circuit connections 14, and conversely.

Whenever it is desired to readjust or change the circuit connections made to either the plug connector 11 or 12, it is to be noted that one may be dissociated from the intermediate connector unit 10 and such plug connections may be readjusted with ease without, however, affecting the plug connections made to the other plug connector 11 or 12. The preferred form of multiple plug construction also enables a large number of circuit connections with a minimum of space without, however, creating the possibility of short circuits. The arrangement in Fig. 14 shows the connectors 10, 11 and 12 associated so that when each series is plugged to maximum capacity, five circuit connections through the wires 13 may be operatively associated with five wires 14 for each row. However, the possibility of ten circuit connections for two rows is not the limitation of the present device and an arrangement will be now described which will point out the extended circuit connecting capacity of the present arrangement.

The arrangement above referred to is shown in Figs. 12, 13 and 14 wherein reference numeral 50 represents a frame which, relative to swinging frames 51 and 52, is stationary. The frame 50 may be mounted in the framework of the machine, a base casting or by other means and is adapted to carry a plurality of the intermediate connectors 10 of the type shown in Figs. 2, 3, 4 and 5. The frame 50 consists of an upper plate 53 and a lower plate 54 (Fig. 14) spaced apart by any suitable means, such as a sleeve 55 fitting over a cooperating fastening bolt and nut 56. Of course, at the other end of frame 50 a similar spacing means is provided. Between the frame plates 53 and 54 of frame 50 there is attached a series of the intermediate connectors 10.

The preferred form of locking means for locking the intermediate connectors in position consists of resilient plates 57 (Figs. 2 and 3) mounted at each end of the connector 10 by the aforementioned tubular rivet 25 or 26. Bent out of each of the plates 57 are locking projections 58 which, as shown in Fig. 3, are semi-circular in form. Each of the plates 57 is provided with a bent-over portion 59 at each end. When the connectors 10 are assembled on the frame 50 between plates 53, 54, the bent-over portions 59 fit beyond the longitudinal edges of the frame plates 53 and 54 (see Fig. 14). The semi-circular locking projections 58 will, through the resiliency of the plate 57, cooperate with circular locking holes 60 formed in the frame plates 53 and 54 (see Fig. 12). Each plate 57 is provided with four locking projections 58 (see Fig. 3) to cooperate with a similar number of holes 60 in the cooperating frame plates 53 and 54 to prevent movement of a connector 10 in either direction. By such fastening means the connectors 10 are rigidly but releasably secured to the frame 50 and may be detached therefrom by manually pressing the portions 59 of the plates 57 away from the cooperating frame plates 53 or 54 to completely disengage the locking projections 58 from the holes 60. The frame 50 may receive and have attached thereto an indefinite number of intermediate connectors 10, depending upon the circuit connecting requirements. The capacity, of

course, can be extended indefinitely, depending upon the length of the frame 50.

Associated with the frame 50 are the aforementioned swinging frames 51 and 52 which are shown to have a movement relative to the frame 50 by virtue of their pivotal mountings 61 and 62 to the frame 50 (Fig. 12). This relative displacement is provided for so that in the manner of a gate the frames 51 and 52 may be swung away from the frame 50 to facilitate the positioning of the intermediate connectors 10. Each of the frames 51 and 52 is adapted to carry plug connectors 11, 12 of the type as shown in Figs. 6-10 and as many connectors of this type are attached to the related frames as is necessary to conform to the circuit connection requirements. In general, there is one of such plug connectors 11, 12 in the frames 51 and 52 for cooperation with the intermediate connector 10 in the frame 50, thereby providing a plurality of multiple plug circuit connecting devices of the elementary system.

The preferred means for attaching the plug connectors 11 or 12 to the frames 51 and 52 will now be described. At the end of each of these connectors there is secured by tubular rivets 63 attaching plates 64 (see Figs. 6, 7 and 8). These are cut out to form fingers 65 and 66 and each plate 64 has a bent-over portion 67. In positioning the plug connector 11 or 12 between the frame plates 70, 71 the fingers 65 and 66 enter in recesses 68 between fingers 69 (see Fig. 12). The recesses 68 and fingers 69 are formed by suitably cutting out the frame plates 70 and 71 of the movable frames 51, 52. Each of the frame plates 70 and 71 is bent as shown in Fig. 12 at 72 so that the recesses 68 and fingers 69 are in the same plane as fingers 65, 66 to provide the positive interlocking relationship of the cooperating elements. When the plug connectors 11, 12 are assembled on either the frames 51 or 52, the bent-over portion 67 cooperates with the outside marginal edge 76 of the frame plates 70 or 71 (see Fig. 14). To firmly lock such plug connectors 11, 12 to the frames 51, 52, there is provided a channel piece 75 which passes over the marginal edge 76 of the frame plates 70 and 71 of frames 51, 52 and by cooperation with the bent-over portion 67 the plug connectors 11, 12 are locked to the frames 51 and 52 to prevent their movement when the frames 51 and 52 are closed upon the frame 50 for making the desired circuit connections through the connectors placed in contacting relationship.

It is obvious, therefore, that when the required number of connectors of the two types previously described are mounted upon their respective frames, multiple circuit connections may be completed through such connectors, depending upon the requirements. The principal advantage of this arrangement is that the plug connections made to the plug connectors 11 carried by the frame 52 may be variously changed while the plug connections to the plug connectors 12 carried by the frame 51 may be unchanged and not interfered with. With the frame 52, for example, carrying several of the plug connectors 11 and with the plug connections made thereto, it is evident that this provides a plugboard with multiple circuit connections made through plugs and related jacks. In the same way the assembly of several plug connectors 12 on the other frame 51 will form a plugboard in which plug connections may be made to the desired jacks. In some electrical systems it is desirable to have one of these plugboards associated with certain electrical elements

by the selective plug connections. The circuit connections can be made through the plug connectors of the type described herein and at the other plugboard 52 selective plug connections are made to other elements of the machine in which it is desirable to change at will the last named described plug connections.

One requirement in which the present arrangement will find particular use is in tabulating machines wherein a number of plugboards are provided, each having plug connections, dependent upon the specific form of tabulating card controlling the machine. In the present arrangement such plug connections may be made on the plugboard of frame 52 and used to control the machine. When the requirement changes this plugboard may be detached from the machine and another one substituted. In such change it is, of course, obvious that the other plugboard remains in permanent electrical connection with the intermediate connectors 10 carried by the stationary frame 50, although, of course, plug connections thereon may be independently changed. The arrangement just described is so flexible in its use that it is evident that it may be utilized in different ways, depending upon the selective circuit requirements of the electrical system.

While there have been shown and described and pointed out the fundamental novel features of the invention as applied to a single embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. A selective circuit connector for multiple circuits comprising an intermediate frame carrying a plurality of intermediate connector units, each comprising a body portion carrying contact members extending oppositely for circuit connections at each side of said body, individual means carried by each of said connector units to lock the latter at desired positions of said frame, a plurality of frames mounted at opposite sides of the intermediate frame and each carrying a plurality of plug connector units carrying contact members cooperating with the related contact members of the intermediate connectors when said frames are releasably joined together, and said plug connector units carrying jacks integral with the related contact members for receiving plugs variously positioned in said jacks, the releasable interconnection of said frames enabling one of said frames to be dissociated from the intermediate frame to enable plug connections on the plug connectors carried thereby to be changed, while the plug connectors on the other frame remain associated with the intermediate connector units of the intermediate frame and its plug connections remain unchanged, and means for collectively locking one or more plug connectors to the related frame at desired positions for cooperation with the intermediate connector units locked at corresponding positions.

2. A circuit connector for multiple circuits comprising a contact support member carrying a single series of spaced contact plates, portions of which project from the plane of said support to provide a series of contact making blades, a cooperating contact member comprising a body, a plurality of teeth extending from one side of

5 said body, each of which bears against adjacent contact blades and retains them separated when said members are joined, said teeth providing intervening recesses for internally receiving a pair of contact blades when said members are joined, contact fingers carried by said body and shaped and arranged in such manner that a pair fitting within the related recess clear each other as they are both inwardly moved by contact with the 10 associated pair of contact blades inserted in the recess when said members are joined, and plug receiving jacks integral with said contact fingers and disposed at the outside of said body.

3. A circuit connector for multiple circuits 15 comprising an intermediate connector unit having a contact support body carrying a single series of spaced contact plates, portions of which project from each side of said body to provide two series of oppositely extending contact making blades, 20 a pair of cooperating connector units disposed at each side of the intermediate connector unit and each comprising a support member having integral blade separating teeth, each of the recesses separating adjacent teeth receiving a pair 25 of adjacent contact blades, contact fingers carried by said support member and shaped and arranged in such manner that a pair of contact fingers within the related recess clear each other as they are both moved inwardly by contact with a 30 pair of blades inserted in the recess when a cooperating connector unit is joined to said intermediate connector unit, and jacks integral with said contact fingers and arranged on the other side of said support member for receiving variously disposed plug connections.

4. A circuit connector for multiple circuits comprising a contact support member carrying a single series of spaced contact plates, portions of which project from the plane of said support to provide a series of contact making blades, a cooperating contact member comprising a body, a plurality of teeth extending from one side of the body, each of which bears against adjacent contact blades and retains them separated when said members are joined, said teeth providing intervening recesses for internally receiving a pair of contact blades when said members are joined, a series of contact fingers extending in said recesses and corresponding in number to the number of contact plates and carried by said body in two spaced and staggered series, one series bent in one direction to make contact with the blades at one side of the recesses and the other series bent in the other direction to make contact with the blades at the other side of said recesses.

5. A circuit connector for multiple circuits comprising a contact support member carrying a single series of spaced contact plates, portions of which project from the plane of said support to provide a series of contact making blades, a cooperating contact member comprising a body, a plurality of teeth extending from one side of the body, each of which bears against adjacent contact blades and retains them separated when said members are joined, said teeth providing intervening recesses for receiving a pair of contact blades when said members are joined, a series of contact fingers extending in said recesses and corresponding in number to the number of contact plates and carried by said body in two spaced and staggered series, one series bent in one direction to make contact with the blades at one side of the recesses and the other series bent in

the other direction to make contact with the blades at the other side of said recesses, and jacks integral with said fingers and arranged on one face of said body in two spaced and staggered series.

HANS P. LUHN.
